(57) **CLAIM**

The ornamental design for a hammer, as shown and described.

DESCRIPTION

FIG. 1 is a side view of a hammer showing the new design, illustrating a handle having an exposed top surface along which its left, right, and bottom edges are polished, a nail pull portion of the hammer having a top surface that is polished, and a striking portion of the hammer having a circumscribing peripheral surface that is polished.

FIG. 2 is a side view of the top portion of the hammer design shown in FIG. 1.

FIG. 3 is a front elevational view of the hammer design shown in FIG. 1.

FIG. 4 is a rear elevational view of the hammer design shown in FIG. 1.

FIG. 5 is a top view of the hammer design shown in FIG. 1.

FIG. 6 is a bottom view of the hammer design shown in FIG.

1.

FIG. 7 is a perspective view of the hammer design shown in FIG. 1; and,

FIG. 8 is an enlarged, perspective view of the striking portion of the hammer shown in FIG. 1.

The areas of the hammer such as grip and the area below the claw are depicted by broken lines because they form no part of the claimed design.
